UNITED STATES PATENT OFFICE.

ARPAD S. MALOCSAY, OF MIAMI, OKLAHOMA.

CHATS-SEPARATOR FOR ORE-JIGS.

1,280,263.

Specification of Letters Patent.

Patented Oct. 1, 1918.

Application filed February 13, 1918. Serial No. 216,890.

To all whom it may concern:

Be it known that I, ARPAD S. MALOCSAY, a citizen of the United States, residing at Miami, in the county of Ottawa and State 5 of Oklahoma, have invented certain new and useful Improvements in Chats-Separators for Ore-Jigs, of which the following is a specification, reference being had to the accompanying drawings.

10 This invention relates to ore separators of the type commonly known as jiggers and in which a vertically oscillating plunger or other suitable means is used for forcing water up through ore resting upon a sieve or 15 grate and the invention particularly relates to the detailed construction of the box which is used for separating the chats from the ore bed.

In this construction of ore separator, there 20 are provided a plurality of cells, each cell consisting of a hutch, a grating extending over the hutch, and a chats separator disposed at the lower end of each grating extending transversely across the grating and 25 formed with a plurality of slots through which the chats are forced, so as to carry the chats away from the ore bed and discharge them separately from the hutch product, and also discharge them separately from the 30 gangue, which is discharged over the top of the separator box onto the ore bed of the next adjacent cell.

The general object of my invention is to provide means for controlling the amount 35 of flush water which is formed into and passes through the chats separator and a further object in this connection is to provide for so controlling the amount of flush water that only a minimum amount need be 40 used, thus making a great saving in expense.

A further object is to reduce the amount of grate surface and thus reduce the cost of the separator or jig, and further to so direct the flush water that any sand which may 45 work through the inlet slots of the chats separator will be discharged or flushed out with the chats and the sand cannot get into the hutch product.

Other objects will appear in the course 50 of the following description.

My invention is illustrated in the accompanying drawings, wherein:—

Figure 1 is a transverse section through an ore separator showing my improved chats 55 separator in section;

Fig. 2 is a longitudinal section through a

separator showing a plurality of cells with the chats separator disposed in said cells;

Fig. 3 is an enlarged longitudinal section of the form of separator box illustrated in 60 Fig. 1;

Fig. 4 is an end elevation of the outer wall of the hutch showing the manner of locking the valve actuating rod;

Fig. 5 is a section on the line 5—5 of 65 Fig. 4;

Fig. 6 is a fragmentary face view of one of the chats separators showing the slide for adjusting the effective area of the slot;

Fig. 7 is a vertical section through Fig. 6; 70

Fig. 8 is a longitudinal sectional view of a modified form of the chats separator box;

Fig. 9 is a longitudinal sectional view of another form of chats separator;

Fig. 10 is a longitudinal sectional view of 75 a further modified form;

Fig. 11 is a view of a portion of the slotted plate 31 shown in Fig. 8.

Referring to the drawings, it will be seen that the jig or separator as a whole is constructed as ordinary jigs are and consists of a plurality of cells. Each of these cells is divided from the next adjacent cell by partitions 10 and each cell communicates at one end with a piston chamber 11, wherein is 80 disposed a vertically reciprocating piston 12, operated in any suitable manner, the reciprocations of this piston causing the water within each cell to pulsate. Across the top of each cell extends a grating 13 and the 90 oscillation of the plunger or piston 12 forces the water up through this grating with considerable rapidity. The valuable portion of the ore being the heavier remains on the bottom of the grating, while the "chats" or "middlings," that is to say, the less valuable portion comprising ore or rock or waste material which adhere to each other, will be forced upward and lie as a stratum on the ore bed. The lighter and waste portion 95

which is utterly valueless, forms a third or top stratum and is carried off with the water over the partition 14 which extends above the grating and over the chats separator box which will now be described. All of the 100 parts heretofore referred to are of any ordinary or suitable construction and form no part of my invention.

One form of the chats separator is illustrated in Fig. 3. The chats separator comprises an elongated box or casing, designated 15, which is open along a portion of 110

its bottom and rests upon the grating 13. The front wall of the box or casing is formed with a plurality of slots 16, the slots extending longitudinally of the separator and being disposed at the height of the chats stratum. Preferably these slots 16 are provided with means whereby the width of the slots may be regulated and to this end I have illustrated a plate or gate 17, mounted 5 upon the face of the outer wall of the chats separator, one of these plates being used for each slot 16 and being vertically slotted as at 18 and the wall of the separator being provided with bolts and nuts 19, thus permitting the gate 17 to be vertically adjusted 10 to control the effective width of the slot 16. Preferably each gate 17 will be formed at its upper end with an outwardly extending flange whereby it may be readily manipulated. 15

One end of the chats separator is open and discharges onto a chute 20, which in turn discharges onto a chute not shown which carries the chats to a suitable place of 20 discharge. The bottom of the chats separator is not entirely open, as is usual with the ordinary form of chats separator, but is partially closed by a longitudinally extending web 21, the under face of which rests 25 flat against the bars of the grating 13 and the upper face of which is downwardly inclined from the inner end of the chats separator to the chute 20. At its inner end this web 21, which forms the bottom of the chats 30 separator, is upwardly extended as at 22. This inner end of the web 21 is spaced from the rear end 23 of the separator box. Co-acting with this upward extension 22 of the web 21 is a gate or valve 24. The under face 35 of this gate or valve is shown as downwardly and outwardly curved, so as to extend approximately parallel to the upper face of the extension 22. It will be seen that when this gate or valve 24 is shifted 40 inward, it will close against the face of the extension 22 and when shifted outward, a passage will be left between the extension 22 and the gate. This gate is illustrated as being mounted upon a longitudinally ex- 45 tending rod 25, which is in turn disposed in suitable guides 26, and the rod 25 extends out through the outer end of the separator box and is there formed with a suitable handle 27. Means are to be provided for holding 50 the rod 25 in any adjusted position and to this end I have shown the rod 25 as notched as at 28 and engaged by a latch 29. This latch, as illustrated in Fig. 5, consists of an eccentric disk and the notches in the 55 handle engage over the adjacent wall and the disk, when turned in one position, binds the handle into engagement with the wall. The disk is formed with an outwardly projecting lug 29, constituting a handle where- 60 by the disk may be manipulated. Any other

suitable fastening device, however, may be used.

In Fig. 3, I have shown the web 21 as being formed with cross rows of upwardly and outwardly discharging passages 30, the 70 passages gradually contracting in cross sectional area, as they extend upward, and gradually curving upward and toward the discharge end of the separator box, the discharge ends of these passages being practically parallel with the surface of the web or bottom 21, so that water discharged through these passages will be directed in jets toward the discharge end of the separator. It will be seen that the upper face of 80 this web 21 is disposed beneath the line of the slots 16.

In Fig. 8, I show another form of this construction. In this case, the web 21 has the upward and rearward extension 22, as 85 previously described, which coacts with the gate 24, which gate operates in the manner previously described. The only difference between the construction shown in Fig. 3 and that shown in Fig. 8, is that in the last 90 named figure the passages 30^a extend upward and forward at a slighter inclination than in Fig. 3, and do not extend forward at their upper ends, but discharge against the face of a slotted plate 31, the upper face 95 of the web 21 being recessed to receive this plate 31.

In Fig. 9, I show still another form of the separator box, wherein the web 21^b is imperforate and not formed with any passages, so 100 that the water forced upward by the pulsations of the piston or plunger pass upward through the rear end of the plate between the rear end of the plate and the wall of the separator and then around the extension 22 105 and the valve or gate 24. Otherwise than this, the construction illustrated in Fig. 9 is the same as heretofore described.

In Fig. 10, I show still another form of the separator box, wherein the bottom or 110 web 21^c at its rear end is upwardly and rearwardly rounded as at 32, so as to form a downwardly flaring opening or mouth for the separator box. The extension 22^a in this case extends straight upward, but is spaced 115 from the upper wall of the box and the rear end wall. The upper face of the web 21^c is downwardly inclined toward the discharge end of the box and disposed above the upper 120 face of the web 21^c is a web 33 which is of the full width of the box and extends longitudinally thereof on a level with the upturned end 22^a of the web 21^c and there is formed with a downwardly extending flange 34, whose rear and under face is rounded 125 off so as to be substantially parallel with the confronting face of the extension 22^a. This web 33 is formed with a plurality of passages 35 which extend downward and forward and controlling these passages and the 130

passage between the extension 22^a and the flange 34 is a valve plate 36. This valve plate is formed with slots 37, which approximately coincide with the slots 35 in the web 33 and the valve plate at its forward end is upwardly turned as at 38 and is connected to the operating rod 25^a. A spring 39 is preferably attached to the rear end of the plate 36 and forces it firmly down upon the upper face of the web 33. It will be obvious now that by shifting the valve plate, the effective area of the slots 35 can be controlled. It is to be understood that the openings or slots 37 of the valve plate are so arranged that when the passage between the extension 22^a and the flange 34 is wide open, then on shifting the valve plate outward, the passage 35^a will first be opened and then the passage 35 will be successively opened, thus giving added impetus to the constantly discharging chats.

In the last named instance the water is forced upward into the rear end of the separator box upon a depression of the piston or plunger and the water flows downward through the passage between the upward extension of the web 21^c and the web 33 and this water, if the openings 35 be opened, will be forced downward to assist in forcing the chats out of the separator. By shifting the valve plate rearward, the area of the passage between 21^c and the web 33 may be controlled, as in the other construction.

This last described form of my invention is the construction which is most suitable for general conditions. It gives the maximum fall to the chats and has, of course, the water controlling feature which is the prime feature of my invention. The construction illustrated in Fig. 9 is to be used on narrow jigs in cells having a relatively thick bead, there being enough fall in the length of the chats separator under these conditions so that all of the flush water necessary is allowed to enter at the rear end of the separator box, there being no necessity for permitting water to enter between this rear end and the discharge end of the box.

While the various constructions which have been heretofore described differ in details, they all have the same underlying and basic principle of water control at the inlet for the water and not at the outlet thereof. In all forms of chats separators known to me, the control has been at the outlet or discharge end and this merely dams the mineral back and there is virtually no water regulation whatever. By controlling the amount of the flush water, I minimize the use of the water and consequently secure a great saving and expense. Furthermore, I secure by the use of my invention, a considerable increase in the effective grate surface because of the narrowness of the chats

separator. It will be seen that the ordinary chats separator reduces the effective area of the grate surface to an amount equal to the area of the base of the chatter resting on the grate. Practically all chatters are at least 70 eight or ten inches wide and therefore take up 240 square inches of grate surface reducing the effective area of the grate surface some 20%. My improved chats separator is about 2" wide and therefore it only covers 75 an area of 60 square inches and reduces the effective area of the grate only about 5% and therefore it will be obvious that with my chats separator, the effective area of the grate is increased. Furthermore, it is obvious that should any sand work through the slots 16, it is flushed out by the chats and cannot get into the hutch product. The main point of this invention resides in the control of the flushing water and in providing means preventing the sand from working down into the hutch product.

While I have illustrated a construction which I have found to be particularly effective in the concentration of lead and zinc sulfids, it will be obvious that many minor changes might be made, without departing from the spirit of the invention.

Having described my invention, what I claim is:—

1. A chats separator for ore jigs comprising a casing formed on one wall with a series of chats receiving openings disposed above the lower edge of the casing, the bottom of the casing being formed with an opening for the inlet of water, and means for controlling the effective width of said water inlet opening.

2. A chats separator comprising a casing open at one end and having a series of chats receiving openings on one side wall, the bottom of the casing having a web extending from the discharge end nearly to the other end of the casing to thereby form a passage at the head end of the casing opening upon the bottom thereof, and means for controlling the inlet of water through said opening.

3. A chats separator comprising a casing open at one end and having a series of openings on one side wall, the bottom of the casing having a web extending from the discharge end nearly to the other end of the casing to thereby form a passage at the head end of the casing opening upon the bottom thereof, and means for increasing or decreasing the effective cross sectional area of said passage.

4. A chats separator comprising a rectangular casing open at one end and having a series of openings on one side wall, the bottom of the casing having a web extending from the discharge end nearly to the other end of the casing to thereby form a passage at the head end of the casing opening upon the bottom thereof, and means for increasing

- or decreasing the effective cross sectional area of said passage, said means including a member longitudinally, shiftable within the casing;
5. A chats separator for ore jigs comprising a casing having a discharge opening at one end and one side wall being formed with a series of inlet openings, the bottom of the casing having a web extending longitudinally from the discharge end nearly to the other end thereof and then being upwardly extended but spaced from the adjacent end wall of the casing to form a water passage, and means coacting with the upward extension of the web for controlling the flow of water through said discharge passage into the space above the web.
6. In a chats separator for ore jigs, a casing having a discharge opening at one end, the bottom of the casing being formed at the opposite end of the casing with a water inlet opening.
7. A chats separator for ore jigs comprising a casing having a bottom and formed with a discharge opening at one end, the bottom of the casing at the opposite end of the casing being formed with a water inlet opening, and means controlling the inlet of water through said opening.
8. In a chats separator for ore jigs, a casing having a discharge opening at one end, a water inlet opening at its other end opening on the bottom of the casing, means for controlling the inlet of water through said inlet opening, said means including a longitudinally shiftable member constituting a gate, a rod extending longitudinally through the casing, by which said member may be adjusted, and means for holding the rod in adjusted position.
9. In a chats separator for ore jigs, a casing having a discharge opening at one end, a water inlet opening at its other end opening on the bottom of the casing, means for controlling the inlet of water through said inlet opening, said means including a longitudinally extending, longitudinally shiftable rod, and means disposed at the discharge end of the casing for holding the said rod in its longitudinally shifted positions.
10. A chats separator for ore jigs comprising a rectangular casing having a discharge opening at one end and closed at the other end, one side wall of the casing being formed with a series of openings spaced from the lower edge of the casing, the bottom of the casing having a longitudinally extending web, the outer face of which is inclined downward and toward the discharge end of the casing, the inner end of said web being spaced from the adjacent wall of the casing to form an inlet opening, and means for controlling the inlet of water through said discharge opening.
11. A chats separator for ore jigs comprising a rectangular casing open at one end and closed at the other, one wall of the casing being formed with a series of openings, the bottom of the casing having a longitudinally extending web, the outer face of which is inclined downwardly toward the discharge end of the casing, the inner end of the web being upwardly extended above the outer face of the web to form an inlet passage, and means for controlling the inlet of water over said upwardly extending portion of the casing, said means being adjustable.
12. A chats separator for ore jigs comprising a rectangular casing having a discharge opening at one end and closed at the other end, one wall of the casing being formed with a series of longitudinally extending slots, a web forming the bottom wall of the casing, the upper face of the web being downwardly inclined toward the discharge opening, the inner end of the web being spaced from the end wall of the casing to provide an upwardly extending inlet opening, means for controlling the inlet of water through said opening, and means for discharging water in jets upon the chats bed on the upper face of the web.
13. In a chats separator for ore jigs, a casing open at one end and closed at the other and formed on one wall with a longitudinally extending series of slots, the bottom of the casing having a longitudinally extending web from the discharge end nearly to the inner end thereof, the inner end of the web being upwardly and rearwardly extended to form a gradually contracting water passage, and adjustable means for controlling the inlet of water through said passage and over the upwardly extending end of the web, the web being formed at spaced intervals with passages extending upward and forward.
14. In a chats separator for ore jigs, a casing open at one end and closed at the other and formed on one wall with a longitudinally extending series of slots, the bottom of the casing having a longitudinally extending web from the discharge end nearly to the inner end thereof, the inner end of the web being upwardly and rearwardly extended to form a gradually contracting water passage, and adjustable means for controlling the inlet of water through said passage and over the upwardly extending end of the web, the web being formed at spaced intervals with passages extending upward and forward, said passages gradually contracting in cross sectional area as they extend upward.
15. A chats separator for ore jigs comprising a rectangular casing having a discharge opening at one end and closed at the other end, one side wall of the casing being formed with a series of longitudinally extending slots, the bottom of the casing having a web extending from the discharge end of the casing nearly to the other end thereof and hav-

ing an upward extension at its inner end, this inner end of the web being spaced from the adjacent end of the casing whereby to provide an upwardly contracted water inlet 5 opening, an adjustable member disposed to coat with the upward extension to reduce or increase the effective water inlet opening, an adjusting rod connected to said adjustable member and extending longitudinally 10 through the casing and at the discharge end thereof, and means for holding said rod in adjusted positions.

16. A chats separator for jigs comprising a rectangular casing having a discharge 15 opening at one end and closed at the other end, one side wall of the casing being formed with a series of longitudinally extending slots, a web forming the bottom of the chats separator and extending longitudinally 20 therealong, the upper face of the web being inclined toward the upper end, the inner end of the web being upwardly extended and spaced from the adjacent end wall to form a water inlet passage, a web extending longitudinally 25 above the first named web and having its inner end spaced from the adjacent face of the upward extension of the first named web to permit water to be discharged over the face of the first named web, said 30 second named web having a plurality of downwardly and forwardly extending openings, and a valve plate mounted upon the upper face of the second named web and longitudinally movable therealong and controlling the passage of water between the webs and through said openings, the plate 35 having openings coating with the openings in the second named web, said openings being so disposed that the openings in the second named web will be successively opened, as the valve plate is shifted longitudinally. 65

18. The combination with a jig, including a cell, a grating extending across the cell and means for causing the pulsation of water in the cell, of a chats separator disposed at the discharge end of the cell and extending 70 across the gratings including a casing having a discharge opening at one end and closed at the other, the front wall of the casing being formed with a series of slots, the bottom of the casing being formed with a 75 web extending from the discharge end nearly to the closed end thereof and then extending upward to thereby provide a water passage between the end of the web and the end wall of the casing, means for controlling the effective water area of said passage, and means for adjusting the effective area of the slotted openings. 80

19. A chats separator for ore jigs comprising a casing having one vertical wall formed 85 with a series of chats receiving openings disposed above the lower edge of the casing, there being an opening at one end of the casing for admitting water, and manually operated means for controlling the effective size 90 of said opening.

In testimony whereof I hereunto affix my signature in the presence of two witnesses.
